UNITED STATES PATENT OFFICE.

AAGE NIELSEN, OF NEW YORK, N. Y.

AUTOMATIC STOP MECHANISM FOR PHONOGRAFS.

1,096,794.

Specification of Letters Patent.

Patented May 12, 1914.

Application filed April 15, 1912. Serial No. 690,715.

To all whom it may concern:

Be it known that I, AAGE NIELSEN, a citizen of the Danish Monarchy, and a resident of the city, county, and State of New York, have invented certain new and useful Improvements in Automatic Stop Mechanism for Phonographs, of which the following is a specification:

This invention relates to improvements in automatic stop mechanisms for phonographs and the object of the invention is to provide a simple automatic stopping device for disk record machines whereby the disk is automatically stopped when the last sound of the record has been emitted.

To this end the invention comprises such elements and combinations of parts as are hereinafter described while reference is had to the accompanying drawings in which—

Figure 1 is a plan view of a disk record phonograph equipped with my stop mechanism with parts removed, and Figs. 2 and 3 are views in elevation of the stop mechanism looking in the direction of arrows 2 and 3 respectively in Fig. 1.

In Fig. 1 the phonograph is represented by the usual disk record 4 and the sound reproducing apparatus or horn 5. The disk is as usual carried by a turntable 60 supported on a pivot 6. The base or box of the machine is not shown; nor is it necessary to describe the operation of the machine which is a matter of common knowledge, as is also the fact that among the numerous records produced, scarcely two are alike; however they all vary according to the length of the musical composition to be reproduced.

It is an object of my invention to provide a simple and effective stop mechanism capable of withstanding ordinary usage, and so arranged as to stop the rotation of the record at a time very soon after reproducing of the record has been completed; my invention insures that the record is not brought to rest before the completion of the reproduction.

Referring to the drawings the numeral 7 represents a bracket or base adapted to be secured to the socket 8 in which the tone tube oscillates by any suitable clamping device 9. The base 7 supports a vertical shaft 10 to which is secured a pulley 11 and a worm 12, which engages with a worm wheel 13 on a horizontal shaft 14 mounted in a bearing 15 and which shaft also carries a worm 16 meshing with a worm wheel 17 on

a second vertical shaft 18. To the latter is fastened a disk 19 and in frictional contact with the disk 19 is another disk 20 which supports a hand 21. A spring 22 supplies the necessary friction to cause the disk 20 to move with the disk 19.

The hand 21 carries a contact 23 and an insulated knob 24. A hook 25, secured to a second hand 26, is adapted to engage the knob 24. The hand 26 also carries an insulated knob 27 and is itself part of a disk 28 in frictional contact with a disk 29 of suitable insulating material and pivoted on a stud 30 in a bracket 31 secured to the base 7. A spring 22 also in this instance causes the friction between the disks 28 and 29. The disk 28 is cut out as at 32, Fig. 1, and on the bracket 31, but insulated therefrom, there is a spring contact 33 adapted to contact with the disk 28 except when the cut out portion 32 is opposite the spring. A third hand 34 is secured in any suitable manner to the horn 5 so as to oscillate therewith and has a hook 35 adapted to engage knob 27 on hand 26.

On the base 7 there is pivoted at 36 an arm 37 of conducting material. The position of the arm 37 with relation to the turntable 60 may be adjusted by means of the pivot screw 36. The arm 37 carries a magnet 38. The magnetic plunger 39 is insulated from the magnet by an insulating sleeve 40. A fixed core 41 is also provided within the sleeve 40 and a spring 42 normally forces the plunger 39 outward against a stop 43 and into a position to act as a stop for a pawl 44 pivoted on a thumbscrew 45 which is secured to the arm 37. A brake-wheel 46 is fixed eccentrically on the thumbscrew 45. A spring 56 tends to throw the brake-wheel against the rotating member 60.

47 is a source of electrical current, such as a small dry battery for instance. The one pole is connected to the one end of the magnet coil. The other end of the latter is connected by wire 49 to the core 41 and the other pole of the battery is connected by wire 50 to the aforesaid contact spring 33 on bracket 31. A pulley 51 is attached to the pivot 6 to rotate with the disk 4 and a belt 52 passes over this pulley and the pulley 11 aforesaid.

The arrangement of the gearing or transmission mechanism carried by the base 7 is such that the hand 21 on the shaft 18 moves at a speed regulated by the speed of the disk

but slower than the speed of the hand 34 which moves with the horn 5. When the stylus is placed in the outer groove of the record the three hands aforesaid are moved 5 toward the record center 6 and brake wheel is turned by the thumbscrew 45 away from the disk and the pawl 44 snaps in behind the plunger 39 as shown in dotted lines. The position of the horn determines the position 10 of the hand 34 which pulls back the hand 26 which pushes back the hand 21. Thus at the start the current is broken. The path of the circuit from the battery through wire 50 to the contact spring 33 is broken between the 15 spring 33 and the hand 26 because of the cut out position 32 in the disk 28. But as soon as the horn begins to move inwardly the hand 26 is rotated by the hand 34, consequently the hand 26 leaves the contact 23, 20 which latter lags behind, but the contact will now be made between the disk 28 and contact spring 33, but not completing the circuit.

During the playing of the record it will be seen that the arm 26 is being pushed 25 ahead by the hand 34 and that the hand 21 follows a slight distance behind as it moves at a slower speed, but the contact is broken all the time between arm 26 and contact 23. The hook 25 is for the purpose of pulling 30 the arm 21 behind the arm 26 in case the former does not for any reason move fast enough. When the horn ceases to swing inwardly toward the center of the record, that is when the last tone has been played the 35 movement of the hands 34 and 26 ceases and they stop, but the hand 21 catches up with them, so to speak, until contact 23 touches arm 26. This closes the circuit from the battery and the current now passes from the 40 latter through 50, 33, 26 and to the arm 21 and from the latter through the base 7 to arm 37, to pawl 44, plunger 39, core 41, wire 49, through the magnet and back to the battery. The closing of the circuit energizes 45 the magnet 38 which pulls up the plunger 39 which frees the pawl 44 and the spring 56 now forces the brakewheel against the turntable and the latter stops together with the disk record. The moment the plunger is 50 withdrawn, the circuit is again broken so that I use the current only for a moment, long enough to energize the magnet.

Inasmuch as the contact 23 contacts with the arm 26 immediately after, but never before the record is played, it will be seen that the latter is stopped as soon as the music ceases, obviously a great advantage. It will have been observed that my invention does not demand any setting or adjusting each time 60 a new record is put on, except that the pawl 44 is moved in behind the plunger.

Changes in the detailed construction may of course be made within the principle of the invention and the scope of the appended 65 claims.

I claim:

1. In a brake the combination with a swinging member and a rotating member, driving mechanism for the latter, a plurality of electric contact elements, one of 70 said contact elements being adapted to be moved in a given direction by the said swinging member, means actuated by the driving mechanism of the said rotating member for moving another of said contact 75 elements in a direction toward said first named contact element and at a speed not greater than that of said first named contact element, a brake for the said rotating member, an electromagnet for controlling 80 said brake, a source of electric energy and electrical connections between the latter, said contact elements and said electromagnet, whereby upon cessation of the inward swinging of the said swinging member the 85 electric circuit through the source and the electromagnet will be completed by the said second contact element overtaking and contacting with the said first contact element.

2. In a brake the combination with a 90 swinging member and a rotating member, driving mechanism for the latter, two electric contact elements, an arm mounted on the said swinging member for moving the first contact element in a given direction, a 95 transmission mechanism interposed between the driving mechanism of the rotating member and the second contact element for moving the latter toward the said first contact element at a speed not greater than that of 100 the latter, a brake for the said rotating member, an electromagnet for controlling said brake, a source of electric energy and electric connections between the latter, said contact elements and electromagnet, whereby upon cessation of the inward swinging of the said swinging member the electric circuit through the said source and the electric magnet will be completed by the said second contact element overtaking and contacting with the said first contact element. 105

3. In a brake the combination with a swinging member and a rotating member, a support, two electric contact elements coaxially mounted on said support, means for 110 rotating one of said contact elements in a certain direction as the said swinging member is swung inwardly over the said rotating member, means for rotating the other of 115 said contact elements in said certain direction, the angular speed of the latter contact element being normally not greater than the angular speed of the said first contact element, means carried by the latter for intermittently accelerating the speed of the said second contact element, a brake for said rotating member, an electromagnet for controlling said brake, a source of electric energy and electric connections whereby upon cessation of the inward swinging of 120 125

- the said swinging member the electric circuit through the source and the electromagnet will be completed by said second contact element contacting with the said first contact element.
4. In a brake the combination with a swinging member and a rotating member, a plurality of movable electric contact elements, means for moving said contact elements in one direction but at different speeds, one ahead of the other while the said swinging member is swung inwardly over the said rotating member, a brake for the rotating member, an electromagnet control-
- ling said brake, a source of electric energy and electrical connections whereby upon cessation of the inward swinging of the said swinging member the electric circuit will be completed by one of the said electric contact elements overtaking and contacting with another of said electric contact elements.
- 10 Signed at New York, N. Y., this 11th day of April 1912.
